UNITED STATES PATENT OFFICE

2,686,656

BLADE LOCKING DEVICE

Robert N. Abild, New Britain, Conn., assignor to
 United Aircraft Corporation, East Hartford,
 Conn., a corporation of Delaware

Application April 4, 1950, Serial No. 153,985

6 Claims. (Cl. 253—77)

1

This invention relates to a device for locking blades in position in a supporting disc and is especially adapted for axial flow compressors or turbines. The rotor for a compressor or turbine is generally made up of one or more supporting discs each having a row of radially extending blades with the roots of the blades fitting in axially extending slots provided in the disc. The blade root is held in the slot by a blade lock which is preferably so constructed that removal of the blade from the disc will not necessitate damaging of either the blade or the disc.

The copending Ledwith application Serial No. 153,795 filed April 4, 1950, having the same assignee as this application, has a blade lock in the form of a strip extending from end to end of the slot that receives the blade root with tabs bent over at each end to engage the ends of the blade root and the sides of the disc. This arrangement is generally satisfactory except in certain cases especially where the blade root is relatively small and where the slot which receives the root is not perpendicular to the sides of the disc in which case the axial thrust on the blade tends to impart a twist to the locking strip within the base of the slot. A feature of this invention is an arrangement for preventing the twisting of the locking strip beneath the blade root. Another feature is an arrangement which eliminates the necessity for any tabs projecting over the ends of the blade root since especially in small size blades there is not always adequate room for the tab.

Other objects and advantages will be apparent from the specification and claims, and from the accompanying drawings which illustrate an embodiment of the invention.

Fig. 1 is a sectional view through a compressor disc showing the lock in position.

Fig. 2 is a perspective view of a portion of the disc with the blade and blade lock separated from the disc but in the proper axial relation.

Fig. 3 is a sectional view along the line 3—3 of Fig. 1.

Fig. 4 is a fragmentary sectional view of a part of Fig. 1 on a larger scale.

Fig. 5 is a bottom view of the blade root.

Fig. 6 is a plan view of the blade lock before insertion in the disc.

The invention is shown in a compressor disc although it will be understood that the invention is equally applicable for the locking of a turbine blade in a supporting disc. As shown, the disc 2 has a plurality of axially extending slots 4, Figs. 2 and 3, which receive the correspondingly

5 2

shaped blade roots 6 which support the radially extending row of blades 8. The blades are positioned in the disc by axial insertion and are held in position by the blade lock 10 hereinafter described in detail.

10 The blade root shown is the type commonly referred to as a dovetail in which the lower part of the blade root is brought to fit in a similarly shaped portion of the slot 4. Both the slot and the blade root narrow down to a relatively narrow neck portion 14 and both the slot and the blade root then widen so that the blade root has shoulders 16 which engage in similar grooves in the disc to support the blade against circumferential movement.

15 The blade lock 10 is in the form of a strip 16 which extends from end to end of the slot 4 and is sufficiently longer than the slot so that the ends may be bent downwardly to form tabs 18, Fig. 4, engaging with opposite side surfaces of the disc 20 between the ends of the lock, the opposite side surfaces having notches 20 which receive projecting ribs 22, Fig. 5, on the underside of the blade root. These ribs are shorter than the length of the blade root as shown so that a portion of the blade lock at each end of the blade root is supported for its entire width between the blade root and the base of the slot in the disc. In this way any tendency of the lock to twist as a result of the forces applied thereon by the axial thrust in the blade is counteracted by the broad end portions of the lock.

20 The preparation of the ribs 22 is not a complicated machining operation since these ribs may be produced by first machining a longitudinal slot 24, Fig. 5, which is the width of the narrow central portion of the blade lock and then by making transverse cuts 26 at opposite ends of the blade root thereby to reduce the length of the ribs 22 to correspond to the length of the notches 20. The blade root may be assembled in the disc by placing the blade lock in position between the ribs 22 with one of the tabs 18 bent downwardly as shown. After the blade has been inserted axially to the proper position the other tab 18 is bent down and the assembly is complete. Disassembly is readily possible either by bending up one of the tabs 18 or by completely breaking it, whichever is more convenient. It may be noted that this blade lock may be bowed somewhat 25 between its ends, as in the case of the blade lock in the copending Ledwith application, above mentioned, for the purpose of maintaining the blade roots snugly in the slot in the disc.

30 35 40 45 50 55 It is to be understood that the invention is not

limited to the specific embodiment herein illustrated and described, but may be used in other ways without departure from its spirit as defined by the following claims.

I claim:

1. In a rotor construction, a disc member having a series of axial slots extending through the disc at its outer periphery, a series of blades extending radially outward from the disc and each having a root member fitting in and engaging one of said slots, and locking means for each blade root to hold it in axial position in the slot, said locking means comprising a flat strip of material extending through said slot and located in the base thereof, said strip having its ends projecting beyond the ends of the slot and having the projecting ends extending over and engaging the sides of one of said members, said strip having a notch between its ends, said other member having a projecting rib thereon engaging with said notch to prevent relative axial movement therebetween.

2. In a rotor construction, a disc member having a series of axial slots extending through the discs at its outer periphery, a series of blades each blade extending radially outward from the disc and having a root member fitting in and engaging one of said slots, and locking means for each blade root to hold it in axial position in the slot, said locking means comprising a flat strip of material extending through said slot and located in the base thereof beneath the blade root member, said strip having its ends projecting beyond the ends of the slot and having the projecting ends extending over the sides of said disc, said strip having at least one recess between its ends, and the blade root member having a cooperating lug engaging with said recess to prevent axial movement therebetween.

3. In a rotor construction, a disc having a series of axial slots extending through the disc at the periphery and a series of blades extending radially outward from the disc and each blade having a root received in one of said slots, said root being shaped to provide a space between the bottom of said root and the base of the slot, in combination with a locking strip positioned in said space with the ends projecting beyond the ends of the slot, said ends extending over and engaging the side surfaces of the disc, said strip having, at least at one side, a notch between its ends, said root having a projection thereon to fit within the notch and thereby prevent relative movement between the blade and the locking strip.

4. In a rotor construction, a disc having a series of axially extending slots in the periphery and a series of blades having roots received in said slots, each root being shaped to provide a space between the bottom of said root and the base of the slot, in combination with a locking strip

positioned in said space with its ends extending over and engaging the side surfaces of the disc, said strip having its opposite side edges notched between the ends and said blade root having spaced projecting ribs thereon corresponding in dimension to the notches in the strip and engaging therewith to prevent relative axial movement between the blade and locking strip.

5. In a rotor construction, a disc having a series of axially extending slots in the periphery and a series of blades having roots received in said slots, each root being shaped to provide a space between the bottom of said root and the base of the slot, in combination with a locking strip positioned in said space with its ends extending over and engaging the side surfaces of the disc, said strip having its opposite side edges notched between the ends and said blade root having spaced projecting ribs thereon corresponding in dimension to the notches in the strip and engaging therewith to prevent relative axial movement between the blade and locking strip, the ends of the strip outwardly of the notches being substantially the full width of the slot in the disc and positioned between the bottom of the blade root and the base of the slot to be held thereby against twisting.

6. In a rotor construction, a disc having a series of axially extending slots in the periphery and a series of blades having roots received in said slots, each root being shaped to provide a space between the bottom of said root and the base of the slot, in combination with a locking strip positioned in said space with its ends extending over and engaging the side surfaces of the disc, said strip having its opposite side edges notched between the ends and said blade root having spaced projecting ribs thereon corresponding in dimension to the notches in the strip and engaging therewith to prevent relative axial movement between the blade and locking strip, the spaced projecting ribs on the blade root terminating at each end at a point spaced from the end of the blade root such that the strip is wider at its ends and at its wider portion is supported between the bottom of the blade root and the base of the groove.
